UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A BASE FOR LAMPS.

SPECIFICATION forming part of Design No. 23,419, dated July 3, 1894.

Application filed June 7, 1894. Serial No. 513,828. Term of patent 3½ years.

To all whom it may concern:

Be it known that I, LOTHAR VON GRAVE, a subject of the Emperor of Germany, residing at Wallingford, New Haven county, in the 5 State of Connecticut, have invented and produced a new and original Design for a Base for Lamps, &c., of which the following is a specification.

In the accompanying drawing, forming 10 part of the specification, the figure is a perspective view of a lamp-base illustrating my design.

15 The essential characteristics of my design consist of a lamp-base the preponderance of which is of leaf-like formation having chasing on the surface thereof and openings therein.

Referring to the drawing, *a* designates the leaf-like formation which constitutes the greater portion of the base, and *b* the chasing thereon. Series of parallel elongated openings *c* are provided in the base and openings *d* extend through the base between various parts of leaf-like portions *a*.

What I claim is—

The design for a base for lamps, substantially as herein shown and described.

LOTHAR VON GRAVE.
